UNITED STATES PATENT OFFICE.

EDWARD R. ARMSTRONG, OF COLUMBUS, OHIO, ASSIGNOR TO F. O. SCHOEDINGER, OF COLUMBUS, OHIO.

VENTILATOR FOR METALLIC WALLS.

Application filed May 22, 1922. Serial No. 562,823.

To all whom it may concern:

Be it known that I, EDWARD R. ARMSTRONG, a citizen of the United States, residing in Columbus, in the county of Franklin, 5 State of Ohio, have invented certain new and useful Improvements in Ventilators for Metallic Walls, of which the following is a specification.

This invention relates to improvements in 10 an improved ventilator structure for sheet metal walls, of the type found particularly in the construction of corn cribs, grain bins and the like.

An object of the invention rests in the 15 provision of a ventilator structure of this character which will possess marked mechanical strength, and possessing an inherent ability to withstand severe pressures and strains and maintain its normal operative 20 condition, at the same time to provide for all necessary ventilation for the passage of air through the wall and exclude rain, moisture or other liquids.

With this and other objects in view the 25 invention consists in the novel features of construction, the combination of elements and arrangement of parts, hereinafter fully described and pointed out in the appended claims.

30 In the accompanying drawing:

Figure 1 is a side elevation of a corn crib and disclosing the walls thereof provided with the ventilator structure comprising the present invention.

35 Figure 2 is an enlarged side elevation of the ventilator structure.

Figure 3 is a vertical section taken on the line 3—3 of Figure 2.

40 Figure 4 is a transverse section on the line 4—4 of Figure 2.

Referring more particularly to the details 45 of the invention, the numeral 1 designates a corn crib or other suitable structure formed to include sheet metal side walls, which latter may be designated by the reference 50 numeral 2. In carrying out the present invention the walls 2 are provided with ventilating openings 3, disposed in staggered relationship and arranged in rows at closely 55 spaced intervals. To provide for the inclusion of the openings 3 so that air may circulate through the corn crib or grain bin, and at the same time to exclude moisture and provide a structure possessing a very consider- 55 able degree of strength, each of the

openings 3 is formed by the inclusion of what may be termed a ventilator structure 4. This structure consists in this instance of a lip 5 of a substantially circular form, which is pressed outwardly of the wall 2 during the process of formation and can be readily accomplished in the manufacture of the wall, so that the lip will be of substantially convex concavo form. In this lip I preferably form a plurality of slits 6, and between these slits the lip is forced inwardly to provide a depressed portion 7, the major portion of which lying in the same plane as the body of the wall 2. The upper end of the portion 7 is joined as at 8 to the upper 70 part of the lip 5, and it will be noted that the said portion 7 is in the transverse section slightly dished to provide a moisture course 9. By depressing the portion 7 it will be observed that the edges 8' thereof will be 75 offset inwardly as compared with the corresponding edges 9' of the lip 5, and between these edges 8' and 9' the air passages 3 are formed through which air may circulate to 80 ventilate the interior of the structure defined by the walls 2. It will be noted that the lip is joined to the wall 2 along substantially circular lines over an extended distance, and it is by virtue of this fact that the rigidity 85 of the lip and its resistance to bending pressures is effected.

By the construction described it will be observed that water traveling downwardly along the exterior surface of the wall 2, upon striking or engaging the lip 5 will be deflected to the greater part away from the openings 3, as the natural tendency of the water is to flow in the course offering the least resistance to its passage. Such water that may flow over the upper part of the 90 lip will be directed into the course 9 formed in the depressed portion 7 and thence led away from the lip without being forced through the openings 3. Again attention is directed to the fact that the ventilator structure does not project into the bin or 95 corn crib 1, but that the major part thereof is disposed to project exteriorly of said bin or crib. This leaves the inner surface of the wall 2 perfectly smooth and free from obstructing projections, enabling the weight of the contents of the bin or crib to rest directly upon the floor and not to be supported to any undue extent by the wall 2 itself. The 100 present invention is particularly an improve- 105 110

ment over past structures utilizing offset tongues, in that the present structure provides for protection against the exclusion of moisture and to an even more important extent provides a strong construction which will withstand successfully strains, pressures and other forces which tend to break down the operative positions of the ventilator.

What is claimed is:

- 10 1. A ventilator structure for sheet metal walls comprising a substantially circular lip integrally formed with and arranged to project outwardly from a sheet metal wall, said lip being provided with a centrally located 15 depressed portion and providing between the lip and said portion a plurality of air passages, the said depressed central portion being disposed in the manner to lie in the same plane as said wall.
- 20 2. In a ventilator structure for sheet metal walls, an outwardly projecting circular lip integrally formed with a sheet metal wall, the center of said lip being depressed so as

to lie in substantially the same plane as said wall, thereby producing a pair of air 25 passageways between the depressed central portion and the outwardly projecting raised portions of said lip.

3. In a sheet metal wall, a ventilator structure therein comprising outwardly projecting substantially semi-circular convexed lips, and a depressed central portion integrally formed with and lying between said lips to produce a plurality of air passageways. 30

4. In a sheet metal wall, a ventilator structure therein comprising an outwardly extending integral lip structure formed to include a pair of wings, and a depressed central portion lying between said wings 40 and disposed in the same plane as said wall, the upper part of said central portion being joined to said lip.

In testimony whereof I have signed my name to this specification.

EDWARD R. ARMSTRONG.
